Primary Examiner — Angela J Lee(74) *Attorney, Agent, or Firm* — Alexander Chen, Esq.(57) **CLAIM**

The ornamental design for an automobile tail light, as shown and described.

DESCRIPTION

FIG. 1 is a perspective view of an automobile tail light;

FIG. 2 is a front view thereof;

FIG. 3 is a side view thereof;

FIG. 4 is a top view thereof; and,

FIG. 5 is a bottom view thereof.

The broken lines are included to show environmental structure and form no part of the claimed design.

The claim includes a second embodiment which is a mirror image symmetrical to the one shown in FIGS. 1-5.

1 Claim, 5 Drawing Sheets(56)
